[57] CLAIM

The ornamental design for a bottle, as shown and described.

DESCRIPTION

FIG. 1 is a view of a bottle showing my design;
FIG. 2 is a top plan view taken on line 2—2 of FIG. 1;
and

FIG. 3 is a view taken on line 3—3 of FIG. 1
The side not shown in FIG. 1 is like the side shown.
The characteristic features of my design reside in the finish and neck portion of the bottle.
